(57) **CLAIM**

The ornamental design for a solar cell with via, as shown and described.

DESCRIPTION

FIG. 1 is a top perspective view that illustrates the solar cell showing our new design;

FIG. 2 is an enlarged fragmental view taken from the designated area in FIG. 1;

FIG. 3 is a top plan view of FIG. 1;

FIG. 4 is a bottom plan view thereof;

FIG. 5 is a rear side elevation view thereof;

FIG. 6 is a front side elevation view thereof;

FIG. 7 is a left side elevation view thereof; and,

FIG. 8 is a right side elevation view thereof.

The dash-dot-dot broken line portion of the figure drawings is included to show boundaries and form no part of the claimed design.

1 Claim, 5 Drawing Sheets
